UNITED STATES PATENT OFFICE.

CHARLES A. KETTERER, OF EAST ST. LOUIS, ILLINOIS.

CONTAINER.

Application filed April 16, 1923. Serial No. 632,578.

To all whom it may concern:

Be it known that I, CHARLES A. KETTERER, a citizen of the United States, and resident of the city of East St. Louis, county 5 of St. Clair, and State of Illinois, have invented certain new and useful Improvements in Containers, of which the following is a specification containing a full, clear, and exact description, reference being had to the 10 accompanying drawings, forming a part thereof.

My invention relates to improvements in containers and has for its primary object a container for holding a refrigerant which is 15 designed to be placed in a display refrigerator and which is equipped with an auxiliary drip-pan located below the container, the drip-pan being so arranged that the depth of the drippings contained therein 20 can be regulated and a predetermined amount of the drippings in the pan retained thus increasing the chilling efficiency.

A further object is to construct a container for refrigerants which is provided 25 with an auxiliary drip-pan, the drip-pan so arranged as to receive all of the drippings from the container and to be movable with the container so that the same can be withdrawn from a refrigerator for charging purposes without allowing the drippings to get 30 on to the floor.

In the drawings:

Fig. 1 is a fragmental longitudinal vertical section through the chilling chamber and 35 part of a display refrigerator with my device in position;

Fig. 2 is a cross section taken on the line 2-2 of Fig. 1;

Fig. 3 is a top plan view of the container 40 with the lid removed and a portion broken away and in section;

Fig. 4 is a cross section taken on the line 4-4 of Fig. 1;

Fig. 5 is a section of a portion of the auxiliary drip-pan and showing the outlet for 45 the drippings and the manner of adjusting the same and

Fig. 6 is an enlarged horizontal section 50 of one corner of the container showing the manner of securing the supporting means.

In the construction of my device I employ a refrigerator having a display chamber 7 and a refrigerating chamber 8. These 55 chambers are separated from each other preferably by means of a reticulated wall 9, this wall allows free circulating of air and

at the same time prevents any of the articles on display from falling into the refrigerating chamber. The top and one side of the display chamber are preferably made 60 of glass so that the contents of the refrigerator can be readily viewed. The refrigerator is provided with a bottom 10 and resting on this bottom and within the refrigerating chamber is a drip-pan 11 65 which is provided with a drain pipe 12. This drain pipe is in turn connected to another pipe, not shown, which carries away the drippings lodging in the pan and discharges it into a sewer or other suitable 70 place for waste water. Extending from the front to the back of the refrigerator and at each side of the chilling chamber are bars 13, these bars preferably have tracks 14 secured thereto, the purpose of these tracks 75 will be explained in detail later.

My receptacle consists of a combined brine and refrigerant chamber 15, this chamber is preferably rectangular in form and is provided with an inclined bottom 16. 80 The top edge of the chamber is preferably folded over upon itself, as indicated at 17, for stiffening purposes. Secured to the outside of the chamber 15 and along each corner are angle irons 18, these angle irons are 85 all of the same length and project above and below the container. Secured to the lower ends of the angle irons 18 is an auxiliary drip-pan 19, this drip-pan is of such size as to snugly fit on the outside of the angle 90 irons, this makes the drip-pan slightly larger than the receptacle 15 so that moisture trickling down the sides of the receptacle will lodge in the drip-pan. Surrounding the upper ends of the angle irons 18 is 95 a skirt or apron 20. The lower end of this apron projects a slight distance below the upper edge of the receptacle 15 and on account of being placed on the outside of the angles, forms a passage way 21. This passage way extends completely around the receptacle 15 except where it is closed at the corners by the angles. The upper edge of the apron is turned inwardly, forming a 100 flange 22. This flange is not only for stiffening purposes but also prevents cutting of the hands while charging the container.

On top of the skirt is placed a lid 23, which is provided with openings 24. These openings permit the entrance of air into the 110 container. The bottom 16 of the container is provided with a plurality of openings 25

through which pipes 26 extend. These pipes are secured to the bottom either by soldering or any other well known manner so that a leak proof joint will be made. Passing 5 through the pipes 26 are tie rods 27, these rods extend entirely through the container 15 and have their ends 28 bent over (see Fig. 4), after which the ends are soldered, so as to prevent moisture from coming 10 through the side walls at the point where the tie rods pass through. Resting on the rods 27 are air pipes 29. The pipes 29 are of less diameter than the pipes 26 and are held in spaced position within the pipes 26 15 by means of a corrugated pipe 30. Within the pipes 29 are air pipes 31, which are of less diameter than the pipes 29 and are held in spaced apart position by means of corrugated pipes 32. It will be noted that 20 some of the pipes 29 and 31 are relatively short and terminate on the same plane with the upper edges of the pipes 26. The short pipes 31 have wires or rods 33 extending therethrough. These rods are arranged at 25 right angles to each other and are for the purpose of preventing pieces of crushed ice from entering the pipes 31. The corrugated pipes 30 and 32 also serve the same purpose, that is, prevent cracked ice from entering 30 the passages between the pipes 26 and 29, and 29 and 31.

Secured to the skirt 20 at the front and back of the container is a bar 34. This bar is longer than the container and has the 35 ends 35 bent around the corner of the container and secured to the skirt. These bars not only tend to stiffen the skirt, but are also for the purpose of either supporting the container directly or having rollers 36 40 attached thereto, which are designed to run on the tracks 14. The container 15 is provided with a drain opening 37 which is normally closed by a cap 38. In this way a considerable amount of brine can be retained in the receptacle 15. The drip-pan 45 19 is provided in one edge near its bottom with a pipe 39, to which is swivelly attached an L shaped pipe 40. This is for the purpose of draining the auxiliary drip-pan or regulating the amount of drippings 50 contained therein. This regulating is done by turning the L shaped pipe on the pipe 39. The position of the open end of the L shaped pipe determining the depth of brine 55 in the auxiliary drip-pan. For instance, if the pipe is in the position shown in solid lines in Fig. 5, the drippings will drain out of the pan and leave the pan substantially dry, while if the open end of the pipe 60 40 is turned so as to be above the bottom of the drip-pan, the distance between the bottom of the pan and the bottom of the open end will be the depth of the accumulation of brine in the pan.

65 When the container is withdrawn for

charging purposes the pipe 40 is turned in the position indicated in dotted lines in Fig. 5, then no brine will pass through the pipe 40 and consequently the container can be withdrawn without any of the brine falling on the floor. After the container has been replaced, the pipe is again turned so as to regulate the amount of brine in the pan 19. It is not desirable to have the pan 19 overflow because in that case, the sides and 75 bottom of the pan would hold a certain amount of brine which would drip on the floor when the container or pan are withdrawn and thus defeat my purpose of making the charging of the container a clean 80 dry job.

The drain 37 is for the purpose of draining the container 15 before recharging with fresh refrigerant and salt for the reason that the brine while chilling the refrigerator will absorb heat units, which will destroy its efficiency as a chilling agent thus allowing fresh cold brine to accumulate after each charge. The drain is also for the purpose of cleaning the container so that the accumulated brine will not become charged with impurities and affect the food stuffs in the refrigerator.

In the drawings I have shown some of the pipes 29 and 31 longer than others, 95 this may however, be varied to suit the requirements in different localities and for the display of different food stuffs, as well as to regulate the humidity of the air within the refrigerator.

100 The operation of my device is as follows:—

My container is charged in the following manner—the drain pipe 37 is first closed by means of a cap 38 after which the container 15 is completely filled with a mixture of cracked ice and salt. This cracked ice and salt will pack itself around and over the various tubes with the exception of the long tubes 31. The ice is also preferably piled high enough to fill a portion of the apron or skirt 20. The brine resulting from the melting of the mixture of ice and salt passes down through the tubes or pipes 26, 29 and 31 which it covers to prevent the formation of any frost therefrom. A certain amount of this brine also passes between the skirt and top of the container 15 and runs along the sides of the container thus removing any frost therefrom. All of the brine then finds its way into the auxiliary drip-pan 19. The depth of which this brine gathers in the auxiliary pan is regulated by means of the pipe connection 40, which has been previously explained. The 110 brine in the auxiliary drip-pan assists in cooling the air within the refrigerator which constantly circulates the cold air traveling along the bottom of the display 115 chamber and as it gradually loses its cold 120 125 130

rising to the top, it then flows along the top of the display chamber and enters the refrigerating chamber where it is again chilled both by coming in contact with the container and also by passing into the container and through the pipes 26, 29 and 31 and out through the bottom of the container. In this way a constant circulation of cold air is maintained and the display chamber maintained at a lower temperature than would be possible were the circulating feature not present.

After the device has been in operation for a time, it will be readily seen that the lower part of the container 15 will become filled with an accumulation of brine until it reaches the top of some of the pipes 26 when it will commence to overflow. The depth of the brine in the container 15 is regulated by the height of these pipes and can be varied for different kinds of installation.

I may also if found desirable, extend all of the pipes 31 to a point near the top 23, or I may make all of the pipes short, this being optional and depending upon the amount of moisture desired in the display chamber and also the rapidity of circulation required. In case of a very slow circulation, all of the pipes are completely covered with ice so that very little air can find its way through them, the air first having to pass through the ice which retards its passage. While by extending the pipes 31 above the ice level a free and unobstructed passage for air is provided through the central tube.

The tie rods 27 stiffen the container to a great extent and prevent the sides from bulging and becoming torn loose from the bottom. This feature is especially essential when installing the device where ignorant help is employed, this help very often being under the impression that the ice and salt must be tamped tightly into the container similar to the manner of packing ice cream. This tamping causing the sides to bulge and also has a tendency to tear the sides away from the bottom.

When it is desired to clean the container, the cap 38 is removed and the brine allowed to drain out, this feature can also be employed where it is not desirable to have an intense cold in the refrigerator, as the resulting brine which is much colder than the ice itself, is allowed to escape quickly and therefore will not produce as much cold within the refrigerator as where the brine is allowed to accumulate and chill the air.

Having fully described my invention what I claim is:-

1. A container comprising a brine and refrigerant chamber having an inclined bottom, angle irons secured to the outside of said chamber and projecting above and below said chamber, an apron secured around said angle irons at their upper ends, said apron surrounding the upper edge of the chamber and spaced apart therefrom by said angle irons, a perforated lid carried by said apron, and an auxiliary drip-pan located beneath said chamber and secured to the bottom of the angle irons, said drip-pan having a greater superficial area than the chamber.

2. A container comprising a brine and refrigerant chamber having an inclined bottom, air circulating pipes extending through and secured to said bottom, said pipes terminating at various heights above the bottom within the chamber, angle irons secured to the outside of said chamber, an apron secured to said angle irons and extending around said chamber adjacent its top and spaced apart therefrom by said angle irons, an auxiliary drip-pan secured to said angle irons below the chamber, a drain for said chamber and means for opening and closing said drain.

3. A container comprising a brine and refrigerant chamber having an inclined bottom, angle irons secured to the outside of said chamber and projecting above and below said chamber, an apron secured around said angle irons at their upper ends, said apron surrounding the upper edge of the chamber and spaced apart therefrom by said angle irons, a perforated lid carried by said apron, and an auxiliary drip-pan located beneath said chamber and secured to the bottom of the angle irons, said drip-pan having a greater superficial area than the chamber, a drain pipe pivotally secured to the auxiliary drip-pan for regulating the level of liquid in said pan.

4. A container comprising a brine and refrigerant chamber having an inclined bottom, air circulating pipes extending through and secured to said bottom, said pipes terminating at various heights above the bottom within the chamber, angle irons secured to the outside of said chamber, an apron secured to said angle irons and extending around said chamber adjacent its top and spaced apart therefrom by said angle irons, an auxiliary drip-pan secured to said angle irons below the chamber, a drain for said chamber, and means for opening and closing said drain, a drain pipe pivotally secured to the auxiliary drip-pan for regulating the level of liquid in said pan.

5. A container comprising a substantially rectangular brine and refrigerant chamber, angle irons secured to the outside of said chamber at its corners, an apron secured to the outside of said angle irons and surrounding the upper portion of the chamber, a perforated lid adapted to fit on said apron, an inclined bottom for said chamber, a plurality of pipes secured to and through said bottom, said pipes terminating at various heights within the chamber, tie rods extend-

ing through the walls of said chamber and through said pipes, a plurality of pipes located within said first mentioned pipes and of less diameter, said pipes resting on the tie rods, corrugated pipes located within the pipes whereby said pipes are maintained in spaced apart position, and an auxiliary

drip-pan secured to the bottom of the angle irons, said drip-pan being of larger superficial area than the chamber.

10

In testimony whereof, I have signed my name to this specification.

CHARLES A. KETTERER,
